FOLDING HIGH CHAIR

John Adler and Dale O. Adler, Grosse Ile, Mich.

Application September 18, 1953, Serial No. 380,991

5 Claims. (Cl. 155—147)

Our invention relates to a new and useful improvement in a folding high chair.

It is an object of the present invention to provide a folding high chair which will be simple in structure, economical in manufacture, durable, easily and quickly moved from folded to unfolded position and vice versa and which will be stable and rigid when moved to unfolded or normal position for use.

Other objects will appear hereinafter.

It is recognized that various modifications and changes may be made in the detail of structure illustrated without departing from the invention and it is intended that the present disclosure shall be considered to be but the preferred embodiment.

Forming a part of this application are drawings in which,

Fig. 1 is a perspective view of the invention in normal useable position.

Fig. 2 is a top plan view of Fig. 1.

Fig. 3 is a side elevational view of the invention.

Fig. 4 is a side elevational view of the invention in process of being folded.

Fig. 5 is a front elevational view of the invention in folded form.

Fig. 6 is a rear elevational view of the invention in folded form.

Fig. 7 is a fragmentary elevational view of Fig. 5 with parts broken away and parts shown in section.

Fig. 8 is a perspective view of a bracket used in the invention.

Fig. 9 is a fragmentary sectional view of a connection used in the invention.

Fig. 10 is a fragmentary view similar to Fig. 3 with parts removed.

Fig. 11 is an elevational view showing the invention in fully folded position.

As shown in the drawings, the invention comprises a pair of legs 7 and 8 which are extended across each other and located at one side of the chair. A similar pair of legs 9 and 10 are extended across each other and located at the other side of the chair, these legs being, at their line of crossing, pivotally connected together by the connecting rod 11. A brace bar 12 serves to connect the legs 8 and 10 and a similar brace bar 13 serves to connect the legs 7 and 9. The legs 8 and 10 may be considered to be the rear legs and the legs 7 and 9 may be considered to be the front legs. The upper ends of the rear legs 8 and 10 are pivotally connected to a lug 15 which is secured to and projects downwardly from the seat 14, the pivotal connection being made by the pivot pin 15-a. Pivoted at one end to this same pivot pin 15-a is a brace bar 16 the upper end of which is pivotally connected to a lug 17 of a U-shaped structure embodying the bight 18. This U-shaped member may be considered a supporting frame as it supports the tray 24 which is detachably mounted thereon. Mounted on the back 27 is an angle plate having the sides 20 and 20-a, the side 20-a having lugs 20-b through which securing means may be projected to secure this plate in fixed relation to the back 27. The lower end of the plate 20 is pivotally connected to a bracket lug 22 which is fixedly mounted on the seat 14. An outwardly bent lug 21 lies in the same plane as the plate 20 and the back 27 is pivoted by means of this lug 21 to the arms 17 of the supporting frame.

Projecting outwardly from the lug 22 is an angularly turned flange 23 which serves as an abutment and which, when the chair is in fully unfolded position, engages the

2

front legs 9 and 7 adjacent their upper ends so as to limit further swinging movement of the various parts. When the chair is in the position shown in Fig. 1, weight placed upon the seat 14 would have a tendency to swing the legs 5 farther apart at their upper ends. This is prevented, however, because of the abutment 23 engaging the legs 7 and 9. Consequently, the chair cannot swing into folded position once it has been fully unfolded and weight is placed upon the seat 14.

10 When it is desired to fold the chair into the folded position a forward pressure on the upper edge of the back 27 will cause the back to rock on its pivotal connection with the upper ends of the legs 7 and 9. At the same time the supporting frame will be carried forward for a slight distance without changing its plane. In this movement, the arms 16 will rock forwardly at their upper ends swinging on their lower pivoted ends. The subsequent movement will cause the rear legs 8 and 10 to move at their lower ends into approach to the lower ends of the front legs 7 and 9. The supporting frame will then rock on its pivotal connection with the back 27 while at the same time the bottom will rock upwardly on the pivot pin 15-a. The movement to folded or unfolded position centers around the pivot pin 32 which pivotally connects the upper ends of the legs 7 and 9 to the lug 28. When in fully folded position, the front and rear legs are substantially in contact and a very compact structure is provided. In order to unfold the chair, it is but necessary, while the structure is resting on the lower ends of the front legs to swing the upper edge of the back 27 upwardly and the various parts will reverse their swinging movement.

20 In the drawings, I have illustrated a swingable part 25 which is mounted on the seat 14 and projects downwardly therefrom and which carries a swingable foot rest 26, the portion 25 engaging against a stop 37. As shown in Fig. 9, the swingable member 25 is provided with a knuckle 62 to receive a pintle 63 mounted under surface on the seat 14.

25 What we claim is:

1. A collapsible high-chair comprising: a pair of supporting front legs and a pair of supporting rear legs, the front legs, intermediate their ends, extending across the rear legs intermediate their ends; a pivot member for pivotally connecting said front legs and said rear legs together at the point of crossing; a seat bottom pivotally connected from the underside thereof, forwardly of its transverse medial line, to the upper ends of said rear legs; a seat back pivotally connected, at its lower edge, to the rear edge of said seat bottom and pivotally connected, above its lower edge and below its transverse medial line, to the upper ends of said front legs; a pair of spaced apart tray supporting-arms pivotally connected to said seat back above the point of connection of said seat back with said front legs and extending forwardly therefrom; and a brace bar pivotally connected, at its lower end, to said seat bottom and to the upper ends of said rear legs and at its upper end to said supporting-arms.

30 2. A collapsible high-chair comprising: a pair of supporting front legs and a pair of supporting rear legs, the front legs, intermediate their ends, extending across the rear legs intermediate their ends; a pivot member for pivotally connecting said front legs and said rear legs together at the point of crossing; a seat bottom pivotally connected from the underside thereof, forwardly of its transverse medial line, to the upper ends of said rear legs; a seat back pivotally connected, at its lower edge, to the rear edge of said seat bottom and pivotally connected, above its lower edge and below its transverse medial line, to the upper ends of said front legs; a U-shaped supporting-frame embodying a pair of oppositely disposed legs, each of said legs being pivotally connected, adjacent one of their ends, to said seat back, above the point of connection of said seat back with said front legs, and projecting forwardly from said seat back; a brace at each side of said seat bottom and pivotally connected at its lower end to the upper ends of said rear legs and to said seat bottom and extending upwardly therefrom and pivotally connected, at its upper end, to the legs of said U-shaped member for maintaining said supporting frame in substantially horizontal position.

35 3. A collapsible high-chair comprising: a pair of sup-

porting front legs and a pair of supporting rear legs, the front legs, intermediate their ends, extending across the rear legs intermediate their ends; a pivot member for pivotally connecting said front legs and said rear legs together at the point of crossing; a seat bottom pivotally connected from the underside thereof, forwardly of its transverse medial line, to the upper ends of said rear legs; a seat back pivotally connected, at its lower edge, to the rear edge of said seat bottom and pivotally connected, above its lower edge and below its transverse medial line, to the upper ends of said front legs; a U-shaped supporting-frame embodying a pair of oppositely disposed legs, each of said legs being pivotally connected, adjacent one of their ends, to said seat back, above the point of connection of said seat back with said front legs, and projecting forwardly from said seat back; a brace at each side of said seat bottom and pivotally connected at its lower end to the upper ends of said rear legs and to said seat bottom and extending upwardly therefrom and pivotally connected, at its upper end, to the legs of said U-shaped member for maintaining said supporting frame in substantially horizontal position; and a stop on the opposite side of said seat bottom adjacent the rear edge thereof and projecting laterally outwardly therefrom for engaging said front legs adjacent their upper ends for limiting relative swinging movement of said front legs and said rear legs in one direction.

4. A collapsible high-chair comprising: a pair of supporting front legs and a pair of supporting rear legs, the front legs, intermediate their ends, extending across the rear legs intermediate their ends; a pivot member for pivotally connecting said front legs and said rear legs together at the point of crossing; a seat bottom pivotally connected forwardly of its transverse medial line, to the upper ends of said rear legs; a seat back; a plate fixedly mounted on opposite edges of said seat back adjacent the lower portion thereof; a forwardly extending lug on said plate; means for pivotally connecting the upper ends of each of said front legs to said lug; a seat bottom; a bracket lug fixedly mounted on opposite side edges of said seat bottom and projecting rearwardly thereof; means for pivotally connecting said bracket lug on the lower end of said plate; a rearwardly extending lug on the upper end of said plate; a substantially U-shaped supporting frame embracing said back and having a pair of oppositely disposed legs projecting forwardly thereof; means for pivotally connecting each of said legs, adjacent the rear ends thereof to said rearwardly extending bracket; means for pivotally connecting the upper ends of said rear legs to

said seat bottom adjacent the forward end thereof; a brace at each side of said seat bottom, each of said brace members being pivotally connected at its lower end to the upper ends of said rear legs and pivotally connected to its upper end to the legs of said supporting frame.

5. A collapsible high-chair comprising: a pair of supporting front legs and a pair of supporting rear legs, the front legs, intermediate their ends, extending across the rear legs intermediate their ends; a pivot member for pivotally connecting said front legs and said rear legs together at the point of crossing; a seat bottom pivotally connected forwardly of its transverse medial line, to the upper ends of said rear legs; a seat back; a plate fixedly mounted on opposite edges of said seat back adjacent the lower portion thereof; a forwardly extending lug on said plate; means for pivotally connecting the upper ends of each of said front legs to said lug; a seat bottom; a bracket lug fixedly mounted on opposite side edges of said seat bottom and projecting rearwardly thereof; means for pivotally connecting said bracket lug on the lower end of said plate; a rearwardly extending lug on the upper end of said plate; a substantially U-shaped supporting frame embracing said back and having a pair of oppositely disposed legs projecting forwardly thereof; means for pivotally connecting each of said legs, adjacent the rear ends thereof to said rearwardly extending bracket; means for pivotally connecting the upper ends of said rear legs to said seat bottom adjacent the forward end thereof; a brace at each side of said seat bottom, each of said brace members being pivotally connected at its lower end to the upper ends of said rear legs and pivotally connected to its upper end to the legs of said supporting frame; and a stop projecting laterally outwardly from said bracket lug for engaging said front legs adjacent their upper ends and limiting relative swingable movement of said front legs and said rear legs.
